L. H. BAKER.

POCKET.

APPLICATION FILED JULY 6, 1915.

1,161,435.

Patented Nov. 23, 1915.

UNITED STATES PATENT OFFICE.

LOUIS H. BAKER, OF EVANSVILLE, INDIANA, ASSIGNOR OF ONE-HALF TO WM. M. SMITH, OF VANDERBURG COUNTY, INDIANA.

POCKET.

1,161,435.

Specification of Letters Patent.

Patented Nov. 23, 1915.

Application filed July 6, 1915. Serial No. 38,103.

To all whom it may concern:

Be it known that I, LOUIS H. BAKER, a citizen of the United States, residing at Evansville, county of Vanderburg, and 5 State of Indiana, have invented certain new and useful Improvements in Pockets, of which the following is a specification.

This invention relates to pockets.

One of the objects of my invention is to 10 provide an improved pocket for the jacket, trousers, or apron of overalls, wherein a plurality of compartments or sub-pockets, arranged in a new relationship, will be provided, adapting the pocket for holding the 15 usual tools, implements or devices which a machinist, engineer, carpenter or other artisan customarily considers should be conveniently carried on the person when overalls are worn.

20 Another object of my invention is the provision of a self-contained pocket, provided with the plurality of sub-pockets or compartments, as previously set forth, and which may be constructed as a separate 25 article of manufacture and applied to the jacket, trousers or apron of overalls or to any garment either by sewing or by the use 30 of buttons or fasteners.

One embodiment of the invention is set 35 forth fully hereinafter and disclosed in the accompanying drawings in which—

Figure 1 is a front view of the pocket, dotted lines showing the lines of seams or stitching for securing the pocket to the garment, and for providing the sub-pockets or 40 compartments; Fig. 2, a view like Fig. 1, showing different implements and devices in the sub-pockets; Fig. 3, a section on line 3—3, Fig. 1; Fig. 4, a section on line 4—4, Fig. 1; Fig. 5, a section on line 5—5, Fig. 1; and Fig. 6, a view like Fig. 1, showing how 45 the pocket may be made separately and attached by buttons or fasteners to the garment.

50 My pocket may be made as a part of the overalls or garment, as shown in Figs. 1 to 5, or, it may be made as a separate and self-contained pocket composed of similar pieces of material which can be attached to any overalls or garment, as in Fig. 6.

The overalls is shown at 1 and the complete pocket at 2. The pocket is provided with the lower sub-pockets or compartments 3 and 4 which have laterally extending or

opening mouths 5 and 6. The pocket 3 is 55 closed at its bottom by stitching 7 and up its side to the point 8 where the opening 5 originates. The pocket 4 is closed by stitching 9 at its bottom which extends up to the point 10 where the lower end of the opening 60 6 originates. The pockets 3 and 4 are separated and demarcated by an intermediate line of stitching or a seam 11 which branches into the seams 12 and 13 that close the tops 65 of the pockets 3 and 4 and form the bottoms 14 for the upper, vertically extending sub-pockets or compartments 14, 15, 16, 17, 18, 19 and 20 which are separated by the parallel, vertical lines of stitching 21. The upper 70 sub-pockets 14, 15, 16, 17, 18, 19 and 20 are provided with mouths 22 (Fig. 5). Stitching 23, together with stitching 7 and 9, secures the complete pocket to the overalls or 75 garment 1.

In Fig. 2, I have illustrated how a watch, 75 calipers, scratch point, rule, pencil, etc., are adapted to be contained in the respective sub-pockets. My pocket is adapted to hold such implements as a scratch point, for instance, so that it cannot endanger the person 80 wearing the overalls.

In Fig. 6, I have illustrated how the pocket may be manufactured separately of similar pieces of material placed face to face and stitched together to form pockets and 85 sub-pockets and afterward secured to the overalls or any other garment by the use of any suitable buttons or fasteners 24, such, for instance, as two-part, penetrating point, self-locking buttons or fasteners such as are 90 commonly known.

I am aware that my pocket is susceptible of modifications and I do not, therefore, limit myself to the details of its construction, but

95 What I claim as new and desire to secure by Letters Patent is:—

1. A pocket comprising lower independent sub-pockets separated by stitching and having separate entry mouths opening in 100 opposite directions, and arranged on substantially the same level, and a plurality of independent compartments or sub-pockets extending in a general up-and-down direction and disposed above the lower sub- 105 pockets and provided with entry mouths at their upper portions.

2. A pocket provided with a central up

and down seam or line of stitching having laterally diverging upper branches defining two lower sub-pockets, said sub-pockets having lateral mouths opening in opposite directions, and up and down lines of stitching whose lower ends join the diverging branches of stitching aforesaid and define

a plurality of upper sub-pockets having closed lower ends, said last-named sub-pockets having mouths at their upper portions.

In testimony whereof, I hereunto affix my signature.
